John Matthews Jr.

John Matthews Jr. of New York, N.Y.
 Letters Patent No. 2166 Dated Sept. 12, 1865
 Design for a Valve Handle.

The schedule referred to in the Letters Patent and making part of the same.

To all whom it may concern.

Be it known that I

John Matthews Jr. of the City, County and State of New York, have invented a new Design for a Handle for Stop Valves, Cocks and Fancits; and I do hereby declare the following to be a full, clear and exact description of same, reference being had to the accompanying drawings forming a part of this specification in which

Figure 1, is a plan view of handle of my design.

Figure 2, is a vertical section of same taken in line 1-2-3, on Figure 1.

Similar letters of reference indicate corresponding parts in both Figures.

The general form of the handle is that of a wheel, the rim of which is formed by a ring, a, having a circular transverse section, intercepted at equidistant points of its circumference by small spherical modules or globes, b, which combine with the ring, a, to prevent somewhat the appearance of beads upon a string.

The modules or globes, b, are united with the hub, c, by a series of straight radial arms, or spokes, d, of circular transverse section.

The hub, d, is of convex or spheroidal form in the transverse section of its periphery and flat and perpendicular to the axis on its upper and lower surfaces.

What I claim as my invention and desire to secure by Letters Patent is,

The design and configuration of the handle, substantially as herein described, and represented by the accompanying drawings.
